UNITED STATES PATENT OFFICE

120,857

DESIGN FOR A BICYCLE STAND

Berry Cohen, Atlanta, Ga.

Application April 1, 1940, Serial No. 91,408

Term of patent 14 years

To all whom it may concern:

Be it known that I, Berry Cohen, a citizen of the United States, residing at Atlanta, in the County of Fulton and State of Georgia, have invented a new, original, and ornamental Design for a Bicycle Stand, of which the following is a specification, reference being had to the accompanying drawing, forming part thereof,

In the drawing:

I claim:

The ornamental design for a bicycle stand, as shown and described.

BERRY COHEN.
